ALOIS GULDEN, OF NEW ULM, MINNESOTA.

GRAIN-SEPARATOR.

1,286,296.

Specification of Letters Patent.

Patented Dec. 3, 1918.

Application filed September 25, 1917. Serial No. 193,141.

To all whom it may concern:

Be it known that I, ALOIS GULDEN, a citizen of the United States, residing at New Ulm, in the county of Brown and State of Minnesota, have invented certain new and useful Improvements in Grain-Separators, of which the following is a specification.

This invention relates to a wheat cleaning device and more particularly to a device 10 for separating wild peas from wheat.

The primary object of the invention is to provide a device that will permit the wheat and wild peas to travel by gravity in a pre-determined course along a spiral trackway 15 in a manner that will cause the light weight wheat to follow the prescribed course while the heavier wild peas due to their greater weight will be ejected over the edge of the trackway.

20 A further object of this invention is the provision of a grain separator which consists of comparatively few parts and is simple in construction, but durable and well adapted to withstand the rough usage to 25 which devices of this character are ordinarily subjected.

For a full description of the invention and the advantages and merits thereof, reference is to be had to the following description 30 and the accompanying drawings, wherein is illustrated the preferred form of my invention, in which:—

Figure 1 is a side elevation of the device constructed in accordance with my invention 35 and showing parts of the same in section.

Fig. 2 is a section taken on the line 2—2 of Fig. 1.

Fig. 3 is a detail view in perspective showing one of the units constituting the trackway.

40 Referring to the drawing wherein is illustrated the preferred form of my invention, and in which like characters of reference 45 indicate like or corresponding parts throughout the several views, a center post or standard 1 is mounted to stand in an upright position and is preferably constructed from a four inch by four inch beam approximately 50 eight feet long. Mounted on the top of the beam or standard 1 is a receptacle 2 designed to hold a quantity of wheat and wild peas. An outlet opening 3 is provided in the bottom 55 of the receptacle and may be opened and closed by a sliding closure 4 mounted

in a suitable casing 5 the wall of which is also provided with opening 6. The slide 4 has an opening 7 adapted to be moved into and out of alinement with the openings 3 and 6 whereby the said openings may be 60 opened and closed to regulate the quantity of wheat and wild peas passing out of the receptacle.

A spiral or helical trackway 8 is mounted on the standard 1 and consists of a plurality 65 of plates shown in detail in Fig. 2 of the drawing and in perspective in Fig. 3 of the drawing. The plates 9 are preferably constructed from suitable thin metal and the side flat faces of the standard have grooves 70 for the reception of the edges of the plate. The grooves 10 are disposed at an angle and are arranged in staggard relation. As shown to advantage in Fig. 2 of the drawing, each plate 9 is substantially trapezoidal in formation and the short longitudinal edge 9' is received in one of the grooves in the standard, while the long longitudinal edge 10' forms the outer edge of the trackway at this particular point. The square end 8' of the 75 plate is overlapped by the angular end 7' of the next adjacent plate and the plates are built up in this manner so that a complete helical trackway is provided. The outer edges 9' and 10' of the plates, as shown 80 in Figs. 1 and 2 of the drawing, are curved slightly to add to the spiral effect.

At the bottom of the standard I have provided a container 11 and in the bottom of this brackets 12 are provided for the reception 90 of the lower end of the standard to hold the standard in upright position. This container 11 is large enough to receive the wild peas as they drop from the trackway 8. The lower end of the trackway is in communication 95 with a chute 13 for conveying the wheat to a point beyond the edge of the container 11.

In operation, the wheat and wild peas will be placed in the receptacle 2 and the sliding closure 4 will be opened to permit the contents of the receptacle to flow onto the trackway 8. By virtue of the spiral construction 100 the wheat will travel down the trackway around the standard 1 and being of comparatively light weight it will follow this prescribed course and pass through the chute 13. The wild peas, however, being of greater weight will be ejected over the edge of the trackway by centrifugal force and thus be 105 110

separated from the wheat. Some of the wild peas will be ejected over the uppermost section of the trackway but others, of course, will not gain sufficient momentum until they 5 have reached a lower portion of the same. It will be understood, that any other grain may be used with the device and any foreign seeds, grain or the like, heavier in weight than the material which is to be preserved, may be used with the device.

10 To facilitate the use of the device I have made the standard 1 collapsible by forming two sections 14 and 15 hinged together at 16 and held in operative position by a 15 tongue 17 fastened to the section 14 and overlapping the section 15 and held to the latter by a removable eye bolt 18. It will be readily apparent that the plates may be 20 taken out of the grooves and as they are all of uniform size, they may be stacked in a comparatively small space and the standard may be folded, the receptacle 2 removed from the top of the standard thus permitting the device to be easily transported from 25 place to place.

From the foregoing it will be observed that a very simple and durable grain separator has been provided the details of which 30 embody the preferred form. I desire it to be understood, however, that slight changes

may be made in the minor details of construction without departing from the spirit of the invention or the scope of the claim hereunto appended.

Claim:

35 A grain separating device comprising a standard substantially square in cross section, and having its flat side surfaces provided with diagonally extending grooves arranged in staggered relation with respect to each other and each equipped with a plate having one marginal edge received in the grooves, the relative positions of the grooves and plates being such as to cause the adjacent ends of the plates to overlap to provide a continuous spiral track-way, the said plates being substantially trapezoidal in 40 formation whereby the ends are overlapped at the corners of the said standards, the said plates being also slightly longitudinally 45 curved to produce a curve in the said track-way when the plates are assembled on the standard.

50 In testimony whereof I affix my signature in presence of two witnesses.

ALOIS GULDEN.

Witnesses:

A. L. Boock,
IDA E. MUESING.
